(57) **CLAIM**

We claim the ornamental design for a case for electronic device, as shown and described.

DESCRIPTION

FIG. 1 is a front, top and right-side perspective view of a case for electronic device showing our new design according to a first, second, third, fourth, fifth, sixth, seventh and eighth embodiment;

FIG. 2 is a front elevational view thereof;

FIG. 3 is a rear elevational view of the case for electronic device according to the first embodiment;

FIG. 4 is a left-side elevational view of the case for electronic device according to the first, second, third, fourth, fifth, sixth, seventh and eighth embodiments;

FIG. 5 is a right-side elevational view thereof;

FIG. 6 is a top plan view thereof;

FIG. 7 is a bottom plan view thereof;

FIG. 8 is a rear, left-side, and bottom perspective view of the case for electronic device according to the first embodiment;

FIG. 9 is a rear elevational view of the case for electronic device according to the second embodiment;

FIG. 10 is a rear, left-side, and bottom perspective view thereof;

FIG. 11 is a rear elevational view of the case for electronic device according to the third embodiment;

FIG. 12 is a rear, left-side, and bottom perspective view thereof;

FIG. 13 is a rear elevational view of the case for electronic device according to the fourth embodiment;

FIG. 14 is a rear, left-side, and bottom perspective view thereof;

FIG. 15 is a rear elevational view of the case for electronic device according to the fifth embodiment;

FIG. 16 is a rear, left-side, and bottom perspective view thereof;

FIG. 17 is a rear elevational view of the case for electronic device according to the sixth embodiment;

FIG. 18 is a rear, left-side, and bottom perspective view thereof;

(Continued)

FIG. 19 is a rear elevational view of the case for electronic device according to the seventh embodiment;

FIG. 20 is a rear, left-side, and bottom perspective view thereof;

FIG. 21 is a rear elevational view of the case for electronic device according to the eighth embodiment; and,

FIG. 22 is a rear, left-side, and bottom perspective view thereof.

In each of the eight embodiments, the small round elements on the rear of the case that are illustrated with the darker lines are indicative of an illuminated state, whereas the small round elements on the rear of the case that are illustrated with the lighter lines are indicative of a non-illuminated state.
